Specification for Design.

Patented Mar. 17, 1914.

Application filed January 14, 1914. Serial No. 812,147. Term of patent 3½ years.

To all whom it may concern:

Be it known that I, WILLIAM H. SAART, a citizen of the United States, residing at Attleboro, in the county of Bristol and State of Massachusetts, have invented a certain new, original, and ornamental Design for a Mesh-Bag, of which the following is a specification.

In the accompanying drawing which forms a part of this specification,—the fig-

ure is a front elevation of a mesh bag showing my design.

I claim:

The ornamental design for a mesh bag, as shown.
